UNITED STATES PATENT OFFICE.

CONRAD SCHÜMMELFEDER, OF OSNABRUCK, GERMANY.

DESIGN FOR A RECEPTACLE FOR SKIN CREAM.

Application filed September 10, 1925. Serial No. 14,745. Term of patent 14 years.

To all whom it may concern:

Be it known that I, CONRAD SCHÜMMELFEDER, a citizen of the German Republic, residing at Osnabrück, in the Republic of Germany, have invented a new, original, and ornamental Design for a Receptacle for Skin Cream, of which the following is a specification, reference being had to the accompanying drawing, forming part thereof.

The figure is a plan view of a receptacle for skin cream showing my new design.

I claim:

The ornamental design for a receptacle for skin cream as shown.

CONRAD SCHÜMMELFEDER.
